EYE SHADE

Roscoe C. Wells, Greencastle, Ind., assignor to Spotswood Specialty Co., Inc., Lexington, Ky., a corporation of Kentucky

Application December 13, 1954, Serial No. 33,527

Term of patent 14 years

(Cl. D57—1)

Fig. 1 is a perspective view of an eye shade embodying my new design;

Fig. 2 is a side elevational view thereof;

Fig. 3 is another perspective view thereof taken on a reduced scale; and

Fig. 4 is a top plan view thereof.

The broken line showing of the spectacles as viewed in Fig. 1 of the drawing is for illustrative purposes only.

I claim:

The ornamental design for an eye shade, as shown and described.
